UNITED STATES PATENT OFFICE.

HARRY J. BORN, OF MERCHANTVILLE, NEW JERSEY, ASSIGNOR TO A. M. COLLINS MANUFACTURING COMPANY, OF PHILADELPHIA, PENNSYLVANIA, A CORPORATION OF PENNSYLVANIA.

DESIGN FOR A CARD MOUNT.

Application filed May 11, 1925. Serial No. 13,388. Term of patent 7 years.

To all whom it may concern:

Be it known that I, HARRY J. BORN, a citizen of the United States, residing in Merchantville, Camden County, New Jersey, have invented a new, original, and ornamental Design for a Card Mount, of which the following is a specification, reference being had to the accompanying drawing, forming part thereof, in which the figure is a face view of a card mount showing my new design.

I claim:

The ornamental design for a card mount, as shown.

HARRY J. BORN.
